VICTOR STANLEY WILLIAMS, OF LONDON, ENGLAND

CASTING MACHINE

Application filed February 5, 1931, Serial No. 513,736, and in Great Britain February 19, 1930.

This invention relates to improvements in casting machines and is more especially concerned with machines for casting stereotypes, but the invention is applicable to other casting machines.

One object of the invention is to provide a simple machine whereby duplicate castings can be made expeditiously and with very little attention on the part of an operative.

According to one feature of the present invention in a casting machine comprising a composite mould, whereof one of the mould parts is movable in a direction substantially normal to the other mould part to open or close the mould, an operating member is provided for moving said movable mould part towards or away from the other mould part, and the movable mould part is mounted on this operating member so as to have freedom of movement in all directions relatively to the other mould part.

Another feature of the invention consists in the provision of a resilient connection between the aforesaid operating member and the mould part carried thereby.

According to yet another feature of the invention, the said movable mould part may comprise a self-adjusting seating for the flong or other matrix.

Mounting the movable mould part aforesaid on an operating member in the way described above enables better castings to be produced than heretofore because a correct seating of one mould part on the other and an equalization of the pressure over the contiguous surfaces of the mould parts is thereby ensured. This advantage is enhanced if the aforesaid resilient mounting is provided between the operating member and the mould part mounted thereon. Further the self-adjusting seating for the matrix is free to tilt so as properly to support the matrix and resist the pressure exerted thereon by the metal as it is admitted into the mould.

In a convenient construction according to the invention for casting stereotypes, the said movable mould part is made in two sections whereof one is movably mounted on the other to permit the insertion of a flong or other matrix between them, and means

is provided for clamping together the matrix and the two sections of the mould part.

For a complete understanding of the invention one embodiment thereof for casting stereotypes will now be described, by way of example, with reference to the accompanying drawings, in which:

Figure 1 is a front elevation of the machine,

Figure 2 is a section on the line 2—2 of Figure 1,

Figure 3 is an elevation of the aforesaid movable mould part,

Figure 4 is a plan of said mould part, and

Figure 5 is a section on the line 5—5 of Figure 4.

Like reference numerals indicate like parts throughout the drawings, which are more or less of a diagrammatic character.

The complete casting machine comprises known or convenient mechanism for delivering intermittently molten metal from a melting pot or other container to a nozzle 10 shown in chain lines in Figure 2 wherefrom the mould is charged. Attached to the nozzle by means of a universal joint is a nozzle plate 11 against which the mould abuts during the casting operation in the usual manner.

The mould is a composite mould comprising two main parts whereof one is a segmental-shaped mould part 58 which is fixed by a screw 85 to a shaft 86 mounted in bearings in the machine frame. This mould part 58, if desired, may be made hollow and be water-cooled. The cooperating mould part is made in two sections, whereof one is a saddle piece 87 which straddles the other section 88; two shoulders 89 being provided on the section 88 to provide seatings for the side limbs of the saddle piece 87. The latter is pivotally mounted about a pin 90 carried by the mould section 88 to permit the insertion of a flong 26 between it and the mould section 88. Thus the saddle piece 87 constitutes a device for holding the flong in position. One end wall of the mould proper is formed partly by a shoulder 91 on the under face of the mould part 58 and partly by the wall 64 of a recess in the saddle piece 87. The other

end wall of the mould is formed entirely by the opposite end wall 92 of said recess. The side walls 13 of the mould on the part 58 are undercut or bevelled to retain the casting

- 5 in that part when the mould parts are separated. The flong 26 and the two mould sections 87, 88 are clamped together by means of an eccentric 93 on the rod 94 which is rotatably mounted in lugs 95 on the saddle 10 piece 87. The eccentric 93 is arranged to bear against a shoulder 96 on the mould section 88. Thus when the eccentric is rotated by means of a knurled knob 97 on the rod 94, the saddle piece 87 and the mould section 88 15 are drawn together and the flong is firmly clamped between them.

The mould part comprising the saddle piece 87 and the mould section 88 is carried by a rod 98 which is slidably mounted in 20 bearings 99 carried by arms 100 which project from trunnions 101 pivotally mounted in the machine frame. At its upper end the rod 98 terminates in a rectangular block 102 which is received loosely between two lugs 25 103 on the mould section 88. These lugs are bored to receive a pin 104 which passes through a slot 105 in the block 102 with sufficient clearance to allow relative freedom of movement in all directions between the block 30 102 and the pin 104. The mould section 88 is also resiliently connected to the rod 98 by means of a spring 106 which is received in a recess 107 in the mould section 88 and bears against the upper face of the block 102. The 35 upper face of the mould section 88 is provided with a recess 108 in which a block 109 is loosely mounted so as to form a self-adjusting seating for the flong 26, the upper face of the block 109 being curved concentrically 40 with the mould part 58.

The rod 98 is moved substantially radially of the mould part 58 to separate the mould parts by means of a cam 110 fixed to a shaft 111. This cam operates a lever 112, one end 45 of which is pivotally connected to a vertical rod 113 mounted in a bearing 114. The other end of the lever 112 is connected by a link 115 to a lever 116, which is fulcrumed on the machine frame and passes through a 50 slot in the rod 98.

In order to adjust initially the mould section 88 relatively to the mould part 58, the rod 113 is screw-threaded intermediate of its ends to receive a nut 117 which is mounted in 55 a slot 118 in the bearing 114 and prevented thereby from movement axially of the rod 113. Also secured to the shaft 111 is a second cam 119 which operates a double-armed lever 120. The latter is articulated at its upper end 60 by a pin-and-slot connection 121 to an arm 122 secured to the shaft 86. The shaft 111 is arranged to be rotated from a shaft 123 carrying a hand wheel 124 by means of toothed wheels 125, 126, the teeth of the latter being 65 formed on the peripheral edge of the cam 119.

An ejector or stripping blade 83 is counterbalanced by a weight 129 and is mounted to swing about pins 130 carried by the machine frame.

The molten metal is delivered into the 70 mould through a hole 127 in the mold part 58, and the supply to the charging nozzle 10 may be controlled by a cam 128 on the shaft 111.

Assuming that a charge of molten metal 75 has just been delivered into the mould, the operator turns the hand wheel 124 in a clockwise direction. This causes the cam 110 to rotate in an anti-clockwise direction and the mould section 88 together with the saddle 80 piece 87 to be lowered substantially radially of the mould part 58 away from the latter. During this separation of the mould parts the casting is retained in the mould part 58 and the latter is stationary. Continued 85 movement of the hand wheel 124 in the clockwise direction brings the cam 119 into operation and the mould part 58 is thereby swung to the left as seen in Figure 2 clear of the other mould part, the ejector 83 being tripped. Subsequently, the mould part 58 returns, and 90 during its return movement the casting is stripped by the ejector 83 from said mould part. The other mould part is then moved upwardly into the position shown on the drawings ready for the next cast, and the 95 sequence of operations just described is repeated.

The invention is not restricted to the precise constructional details described as obvious changes can be made therein without departing from the invention. 100

I claim.

1. In a casting machine, the combination with a composite mould whereof one of the mould parts is movable in a direction substantially normal to the other mould part to open or close the mould, of an operating member for moving said movable mould part towards or away from the other mould part, on which operating member the movable mould part is mounted so as to have freedom of movement in all directions relatively to the other mould part. 105

2. In a casting machine, the combination with a composite mould whereof one of the mould parts is movable in a direction substantially normal to the other mould part to open or close the mould, of a rod on which said movable mould part is mounted so as to have freedom of movement in all directions relatively to the other mould part, a guide in which said rod is slidably mounted in the direction of its axis, and means for moving said rod in its guide to carry the movable mould part towards or away from the other mould part. 110

3. A casting machine having a composite mould one part of which is movable in a direction substantially normal to the other part, 115

an operating member carrying the movable mould part, a resilient connection between the operating member and said movable mould part, and means for actuating the operating member to open or close the mould.

5 4. A casting machine having a composite mould one part of which is movable in a direction substantially normal to the other part, a slidably mounted rod on which said movable mould part is resiliently mounted with freedom to move in all directions relatively to the other mould part, and cam-controlled means for actuating the said rod to carry the movable mould part towards or away from

10 the other mould part.

15 5. In a casting machine having a mould part which is movable in a direction substantially normal to a cooperating mould part to open or close the mould, a self-adjusting seat-

20 ing for a matrix in the said movable mould part.

25 6. In a casting machine, the combination with one part of a composite mould of a co-operating movable mould part, a self-adjusting matrix seating in said movable mould part, and an operating member on which the movable mould part is mounted so as to have freedom of movement in all directions relatively to the other mould part.

30 7. A casting machine comprising a composite mould whereof one mould part is movable in a direction approximately normal to the other mould part, an operating member on which the said movable mould part is mounted so as to be free to move in all directions relatively to the other mould part, which movable mould part is made in two relatively movable sections arranged to receive a matrix between them, clamping means

35 to clamp the matrix and said two mould-sections together, and means for actuating said operating member to open or close the mould.

40 In testimony whereof I affix my signature.

45 VICTOR STANLEY WILLIAMS.
